FIRE EXTINGUISHER

Charles L. Burgoyne, Norwood, Ohio

Application February 18, 1949, Serial No. 77,245

8 Claims. (Cl. 169—30)

1

The present invention relates to a fire extinguisher including an extensible nozzle adapted to actuate the extinguisher release valve.

The primary object of the invention is to provide a fire extinguisher having a cylinder charged with a fire extinguishing agent under pressure which is releasable from one end of the cylinder by means of a valve, and wherein the cylinder carries an extensible nozzle adapted upon extension thereof to open the valve.

A further object of the invention is to provide a hand type fire extinguisher having a cylinder containing a fluid fire extinguishing agent under pressure and also having a nozzle slidably mounted on the cylinder in surrounding relation thereto for directing the fire extinguishing agent onto the fire, and wherein extending the nozzle effects opening of a valve adapted to release the fire extinguishing agent for flow from the cylinder and through the nozzle.

Another object of the invention is to provide a fire extinguisher having a cylinder charged with a fire extinguishing agent under pressure and which is releasable from the cylinder only by extension of an extensible nozzle mounted in surrounding relation with respect to the cylinder, and wherein means are secured to the cylinder to releasably retain the nozzle in the non-extended position.

Another object of the invention is to provide a compact hand type fire extinguisher in which a charged cylinder or container carries a slidably tubular nozzle adapted to be extended for directing the fire extinguishing agent onto the fire while maintaining a safe distance between the fire and the person holding the fire extinguisher.

Another object of the invention is to generally improve the convenience of operation and simplicity of construction of fluid charged, hand type fire extinguishers.

The above and other objects of the invention will become apparent upon reading the following detailed description in conjunction with the accompanying drawing, in which:

Fig. 1 is a longitudinal cross sectional view of a fire extinguisher embodying the principles of the present invention.

Fig. 2 is an elevation view of a fire extinguisher embodying the principles of the present invention and illustrating a slightly modified construction.

For a description of the invention reference is made to Fig. 1, illustrating a hand type fire extinguisher having an elongated cylinder 1 closed at the upper end by a domed wall 2 and 55

at the lower end by a cap 3 welded or otherwise secured to the cylinder and providing an upwardly facing annular shoulder 4. The cap or closure 3 is provided centrally thereof with a boss 5 which is centrally apertured and threaded to receive the upper threaded end portion of a valve 6. Between an upwardly facing shoulder and the lower end of boss 5 is a gasket 7 to prevent leakage of fluid at this point. The valve body has a straight-through fluid passage 8 and midway thereof is rotatably mounted a plug 9 having a transverse passage 10 therein which is adapted to be aligned with the fluid passage 8 upon rotation of the plug 9. Externally of the valve body the rotatable plug 9 is connected rigidly to a valve actuating arm 11, having a ball-shaped enlargement 11' on the free end thereof. The lower end of the valve body carries a threaded nipple 12 for use in making a secure connection with the valve when the cylinder 1 is to be charged with a fire extinguishing agent, such as carbon dioxide. The release valve including a rotatable plug is only one possible type of on-and-off valve that may be used. If the rotatable plug type of valve is carefully constructed and assembled it is quite suitable for this purpose.

Slidably mounted over the cylinder 1 is a sleeve or tube 13 having an inside diameter just 30 slightly greater than the outside diameter of the cap member 3. The tube 13 when extended in the direction of the arrow A serves to first turn on the valve 6 and then to direct the fire extinguishing agent onto the fire. The tube may 35 thus be termed a combined valve actuator and nozzle. When fully extended it enables a person to apply the fire extinguishing agent directly to a small fire and still not require that the person stand too close to the fire. The upper end of the sleeve 13 is provided with a bead-like formation 14 terminating in an annular flange 15 adapted to slidably fit the outside of cylinder 1. Just below the bead formation 14 a ring 16 is welded or brazed inside the sleeve 13. This ring not only serves to strengthen the thin walled sleeve 13 but also provides a definite stop means for the fully extended position of the sleeve as the lower edge of the ring comes into abutment with the annular shoulder 4 of the cap 3.

In order to retain the sleeve 13 in the retracted position, as shown, a pair of spring latches or spring arms 17 and 18 are provided and are securely attached to the cylinder 1. The latches 17 and 18 are formed to fit over and around the

bead formation 14 and also include cam portions 17' and 18' on the free ends to lift the latches into latching position as the sleeve 13 is forced up to engage the latches. The spring arms 17 and 18 are preferably formed at opposite ends of a metallic strip extending over the top of the cylinder 1 and wall 2, and secured thereto as by welding, brazing or soldering. Midway of its length the strip is formed with an upwardly extending loop or ring 19 for use in hanging the extinguisher on a hook or other supporting device.

In order to control the release valve 6, the sleeve or nozzle 13 is provided at the lower end with an annular recess 20 having upper and lower walls 21 and 22 and an outer wall 23. The end portion 11' of the valve actuating arm 11 normally fits into the recess 20, as shown in Fig. 1. The lower wall portion 22 prevents any downward movement of the arm 11, as long as the sleeve 13 is retained in the upwardly extended position by the latches 17 and 18. However when the sleeve 13 is released from the latches, the sleeve may then be pushed downwardly in the direction of the arrow A whereby the circular wall 21 contacts the handle end portion 11' and thus turns the handle 11 in the direction of the arrow B. The valve plug 9 is thus caused to rotate in a direction to open the valve 6. By the time the valve 9 is fully open the end portion 11' of the arm 11 is in contact with the inside of the sleeve 13, and when the sleeve is fully extended the ring 16 is in abutment with the upper end of the cap 3. As the fire extinguisher goes into action the fire extinguishing agent flows from the end 12 of the valve 6 and flows outward through the sleeve 13 onto the fire.

In order to charge the cylinder 1 the sleeve 13 is retracted part way, so that a connection with the threaded end portion 12 may be completed. After the cylinder is full as indicated by its weight, or by the reduction in pressure at the charging cylinder, the sleeve 13 is fully retracted at the same time the arm end 11' is manipulated into the annular recess 20. The preferred fire extinguishing agent is carbon dioxide although other agents, such as methyl bromide or chlorobromomethane may be used if desired. The agent should be capable of free flow from the valve 6 under gaseous pressure as soon as the valve is opened, and should be capable of efficiently excluding air from the fire.

In Fig. 2 of the drawing there is shown a fire extinguisher like that of Fig. 1 except for two specific features. The upper rim of the sleeve 13' is provided with a symmetrical double cam formation 30 having a central low point 31 normally occupied by a short pin 32 rigidly connected to the cylinder 1'. On either side of the low point 31 the cam has an inclined cam surface. In releasing the sleeve 13' from the latches 33 and 34, the sleeve 13' may be turned in either direction to force the sleeve away from the pin 32 and downwardly with respect to the spring latches 33 and 34. Thus the cam formation and the fixed pin cooperate to cause disengagement of the sleeve and the spring latches merely by rotation of the sleeve prior to sliding the sleeve outwardly for operation of the releasing valve. If desired the cam formation 30 and the relatively fixed pin 32 may be provided at diametrically opposite points of the fire extinguisher, to provide a more effective nozzle releasing action.

Another feature shown in Fig. 2 is the elimina-

tion of the annular recess 20 of the first described embodiment. In place of this construction the sleeve 13' of Fig. 2 is merely provided with a slot 35 extending part way around the sleeve near the lower end thereof. The valve operating arm 36 extends through the slot 35 when the sleeve 13' is in the retracted position as shown. Furthermore the arm 36 has its free end rounded off at the lower side thereof, as at 36'. The threaded nipple 12' is provided for the discharge end of the valve, and as in Fig. 1 the fire extinguisher is adapted to be supported from a loop 19' when not in use. To use the fire extinguisher one merely removes it from a hanger and grasps the device with one hand around the sleeve 13' and the other hand around the upper end of the cylinder 1'. The sleeve 13' is then rotated in either direction while the lower end of the sleeve is directed toward the fire. Then as the latches 33 and 34 release their grip on the upper end of the sleeve 13' the sleeve is then manually forced outwardly toward the fire to the limit of its sliding movement. In rotating the sleeve 13' the arm 36 moves within the slot 35 but no opening movement of the valve occurs until the upper edge of the slot impinges on the upper side of the arm 36. As the sleeve 13' is forced outwardly the arm 36 is automatically rotated to open the release valve and the rounded end portion 36' is free to move into the sleeve without jamming against the lower edge of the slot 35. While the cam formation 30 provides means to facilitate easy release of the sleeve from the spring latches, it is optional whether the sleeve is released by initial rotation. A direct downward force will cause release of the latch devices from the sleeve just as in the form of the extinguisher shown in Fig. 1. In both forms of the invention the principal advantages are the compactness and operating simplicity of the extinguisher. There is no projecting horn or nozzle to break or to take up space. The only operating instruction needed is to slide the outer sleeve in the direction of the fire while holding the cylinder securely at its upper end.

The embodiments of the invention herein shown and described are to be regarded as illustrative only and it is to be understood that the invention is susceptible of variations, modifications and changes within the scope of the appended claims.

I claim:

1. A fire extinguisher comprising, a closed cylinder adapted to contain a fluid fire extinguishing agent under pressure, a valve at one end of said cylinder operable to release a stream of said fire extinguishing agent, valve actuating means movably mounted on said valve, a tubular nozzle closely surrounding said cylinder and slidably longitudinally thereof for extension beyond said one end of the cylinder, and means on said nozzle engageable with said valve actuating means to operate said valve upon sliding movement of said nozzle to the extended position.

2. A fire extinguisher as recited in claim 1, including latch means to releasably retain said tubular nozzle in the non-extended position.

3. A fire extinguisher as recited in claim 1, including a spring latch movably mounted on said cylinder for engagement with a projecting portion of said tubular nozzle to releasably retain said nozzle in the non-extended position, and cam means on said tubular nozzle for engagement with a fixed element on said cylinder to move said nozzle toward the extended position upon rotation of said nozzle with respect to said cylinder, to

thereby effect release of said spring latch from said projecting portion of said nozzle.

4. A fire extinguisher comprising, a closed cylinder adapted to contain a fluid fire extinguishing agent under pressure, a valve at one end of said cylinder on the central axis thereof and operable to release a stream of fire extinguishing agent, a valve operating arm movably mounted on said valve and extending away from the central axis of said cylinder in the closed position of said valve, a tubular nozzle closely surrounding said cylinder and slidably longitudinally thereof for extension beyond said one end of the cylinder, and an annular recess internally of said tubular nozzle beyond said one end of the cylinder to receive the outer end of said valve operating arm, whereby a sliding movement of said nozzle to the extended position effects operation of said valve to release said stream of fire extinguishing agent for flow from said valve and outwardly through said tubular nozzle.

5. A fire extinguisher comprising, a closed cylinder adapted to contain a fluid fire extinguishing agent under pressure, a valve at one end of said cylinder operable to release a stream of said fire extinguishing agent for flow from said cylinder, valve actuating means movably mounted on said valve, a tubular nozzle slidably longitudinally of said cylinder for extension beyond said one end of the cylinder, means on said nozzle engageable with said valve actuating means to operate said valve, and said nozzle providing means to direct said fire extinguishing agent onto a fire upon operation of said valve to open position by sliding movement of said nozzle to the extended position.

6. A fire extinguisher comprising, a closed cylinder adapted to contain a fluid fire extinguishing agent under pressure, valve means rigidly mounted on said cylinder and including valve actuating means operable to release a stream of said fire extinguishing agent from said cylinder at one end thereof, a tubular nozzle closely surrounding said cylinder and slidably longitudinally thereof for extension beyond said one end of the cylinder, whereby said stream of fire extinguishing agent may be directed onto a fire by passage outwardly through said nozzle in the extended

position thereof after said valve actuating means has been operated to open said valve.

5 7. A fire extinguisher comprising, a closed cylinder adapted to contain a fluid fire extinguishing agent under pressure, valve means rigidly mounted on said cylinder and including valve actuating means operable to release a stream of said fire extinguishing agent from said cylinder at one end thereof, a tubular nozzle closely surrounding said cylinder and movable longitudinally thereof for extension beyond said one end of the cylinder, and means on said nozzle engageable with said valve actuating means to open said valve means upon movement of said nozzle relative to said cylinder, whereby said stream of fire extinguishing agent is released for flow from said valve means and outwardly through said tubular nozzle.

10 8. A fire extinguisher comprising, a closed cylinder adapted to contain a fluid fire extinguishing agent under pressure, a valve at one end of said cylinder substantially on the central axis thereof and operable to release a stream of said fire extinguishing agent, a valve operating arm movably mounted on said valve and extending away from the central axis of said cylinder in the closed position of said valve, a tubular nozzle closely surrounding said cylinder and slidably longitudinally thereof for extension beyond said one end of the cylinder, means on said tubular nozzle beyond said one end of the cylinder engageable with said valve operating arm, whereby a sliding movement of said nozzle to the extended position effects operation of said valve to release said stream of fire extinguishing agent for flow from said valve and outwardly through said tubular nozzle.
